HOLDER FOR LADY'S MAKE-UP ARTICLES

Filed April 7, 1950

Attorney

UNITED STATES PATENT OFFICE

2,609,578

HOLDER FOR LADY'S MAKE-UP ARTICLES

Sarah S. Andary, Winter Park, Fla.

Application April 7, 1950, Serial No. 154,560

2 Claims. (Cl. 24—81)

1

This invention relates to a novel holder or clip adapted to be carried in a handbag for holding such articles for make-up as a lipstick, lipstick brush, lipstick blotting paper and a mirror so that all such articles will be conveniently available when the holder is withdrawn from the handbag thus eliminating the inconvenience commonly occurring in attempting to locate all of such articles when loosely and separately containing in a handbag.

A further object of the invention is to provide a resilient holder or spring clip of unique construction having a novel means for releasably holding lipsticks of various sizes and wherein the lipstick case retains the lipstick holding portion of the clip in a properly adjusted position for holding the particular lipstick case.

Still a further and important object of the invention is to provide a spring clip or resilient holder wherein certain of the elements engaged thereby will cooperate with the clip structure for more effectively holding other elements which are supported by the clip.

Still a further object of the invention is to provide a device of the aforescribed character which is of extremely simple construction and capable of being very economically manufactured and sold and which will be extremely efficient and durable for accomplishing its intended purpose.

Numerous other objects and advantages of the invention will hereinafter become more fully apparent from the following description of the drawing, illustrating preferred embodiments thereof, and wherein:

Figure 1 is a front elevational view showing the holder or clip supporting a lipstick, lipstick brush and mirror;

Figure 2 is an end elevational view thereof looking from left to right of Figure 1 and on an enlarged scale;

Figure 3 is a horizontal sectional view taken substantially along a plane as indicated by the line 3—3 of Figure 2;

Figure 4 is a vertical sectional view taken substantially along a plane as indicated by the line 4—4 of Figure 2;

Figure 5 is a fragmentary horizontal sectional view of a modified form of the holder, and

Figure 6 is a view similar to Figure 5 but illustrating another modification.

Referring more specifically to the drawing, and first with reference to the embodiment thereof as illustrated in Figures 1 to 4, the resilient holder or spring clip in its entirety and which comprises the invention is designated generally 7 and in-

cludes an elongated strip of any suitable resilient material such as spring steel having an intermediate part forming an inverted U-shaped portion, designated generally 8 and including an upper or intermediate arcuate portion 9 and depending legs 10 and 11 which are spring biased toward one another by the resiliency of the resilient strip. The leg 11 is longer than the leg 10 and terminates at its lower end in an integral turned back portion 12 which extends upwardly along the outer side of the leg 11 to above said intermediate portion 9 and the upper end portion 13 of which is bowed above the upper end of the leg 11 so as to normally be disposed directly above a part of the intermediate clip portion 9. The resiliency of the strip forming the clip 7 causes the turned back portion 12 to be normally disposed against the leg 11. The portion 13 terminates at its upper free end in an outwardly turned back terminal portion 14 of the strip which constitutes, with the upper portion of the turned back strip part 12 a secondary spring clip, designated generally 15. The clip leg 14 has an upper portion 16 which is bowed in the same direction as the portion 13 and therebelow includes a substantially straight portion 17 which extends obliquely toward the portion 12 and terminates in an outwardly flared terminal portion 18 which constitutes one terminal of the strip. The clip leg 14, adjacent its terminal 18 normally bears resiliently against an intermediate part of the turned back portion 12 and is spring biased by the resiliency of the strip toward said outer leg portion 12.

The leg 10 terminates at its lower end in a turned back outer leg portion 19 which extends upwardly along the outer side of said leg 10 and which is yieldably urged toward the leg 11 and normally disposed in abutting engagement therewith. Said outer leg portion 19 extends to above the upper end of the leg 10 and thereabove is provided with an inwardly bowed portion 20 which is bowed opposite to the portion 13 and which extends toward and is disposed in face adjacency to the portion 13. Said arcuate portion 20 in turn terminates in an outwardly turned back portion 21, similar to the portion 16 but which extends downwardly only to about the level of the intermediate portion 9 and which terminates at said point in an outwardly turned upwardly bowed portion forming a jaw 22 which is disposed transversely of the longitudinal axis of the clip 7 and which extends laterally therefrom.

The leg 10 has an intermediate portion which 55 is reduced in width and narrower than the outer

55

leg portion 19, as seen at 23 and best illustrated in Figure 3. A second jaw 24, corresponding to the jaw 22 and which constitutes a separate part from the strip forming the parts 9 to 22, inclusive, is disposed below the jaw 22 and is provided at its inner end and side edges with complementary inturned hook portions 25 which engage around the side edges of the outer leg portion 19 and which extend into the recessed side edges of the leg 10, provided by the reduced portion 23, for slidably supporting the jaw 24 on said outer leg 19 and beneath the jaw 22. The jaws 22 and 24, as seen in Figure 2, are bowed in opposite directions or away from one another and terminate at their outer ends in outwardly flared terminal portions 26 which constitute reverse bends of the jaws 22 and 24 and which form the open mouth of the clamp, designated generally 27 and which is formed by said jaws 22 and 24.

The inner or adjacent sides of the legs 10 and 11 are lined with cushioning pads 28 which may be formed of rubber, felt or any other suitable material and which are suitably bonded to the adjacent sides of the legs 10 and 11.

The portions 16 and 21 form thumb and finger rests and it will be readily apparent that said portions may be gripped between the thumb and finger and thereby displaced toward one another to exert pressure on the clip legs 10 and 11 for displacing said legs away from one another; the clip legs 10 and 11 being normally disposed and spring biased toward converging relationship. By thus spreading the legs into diverging relationship, a mirror 29 or any other suitable relatively thin article such as a vanity case, compact or wallet, not shown, may be inserted between the legs 10 and 11 after which the pressure is released on the portions 16 and 21 to allow the legs to be spring biased by their resiliency toward one another so that a part of the mirror 29 will be clamped between the pads 28. The normal tendency of the clamp jaw 24 will be to slide downwardly on the outer leg portion 19 and away from the upper jaw 22, this downward sliding movement being limited by the hooks 25 engaging the widened lower end of the leg 10. Accordingly, it will be readily apparent that a conventional lipstick containing barrel or case 30 may be inserted between the jaws 22 and 24 after which the jaw 24 is displaced upwardly so as to clamp the case between said jaws. This will cause the upper jaw 22 which is yieldably supported by the portion 21 to yield upwardly so that it will be spring biased downwardly to yieldably grip the case 30 and through said case to exert a pressure on the lower jaw 24 which will cause said lower jaw to rock clockwise as seen in Figure 2 where the hooks 25 engage the side edges of the outer leg 19 to cause said hooks to be thereby canted and brought into frictional and gripping engagement with the leg 19 to hold the lower jaw 24 in a raised and adjusted position for gripping the lipstick case 30. It will thus be readily apparent that the lipstick clamp 27 provides a resilient clamp for yieldably engaging a lipstick case and also an adjustable clamp for holding lipstick cases of different cross sectional sizes or diameters. The portions 13 and 20 combine to form resilient clamping jaws for a conventional lipstick brush 31 the handle of which is inserted downwardly between said portions 13 and 20 so as to rest upon the upper, convex side of the intermediate portion 9 and to be yieldably gripped between the upwardly converging parts of said portions 13 and 20, as il-

lustrated in Figure 2, so that the lipstick brush is held yieldably in its applied position of Figures 1 and 2. Additionally, the lipstick brush 31 exerts a spreading force on the portions 13 and 20 which not only tend to increase the resilient gripping engagement of the legs 10 and 11 with the mirror 29 and to substantially prevent said legs from being sprung apart to release the mirror until the brush 31 has first been removed, but additionally increases the spring action on the clamp jaw 22 exerted by the portion 21 for biasing said jaw 22 toward the jaw 24. The leg 14 of the clip 15 may then be sprung away from its coacting clip leg 12 and in so moving will tend to displace the portion 12 away from the leg 11, as illustrated in dotted lines in Figure 2, so that a pad or number of plies of lipstick blotting paper 32 may be inserted in the clip 15 between its jaws 12 and 14 and will be releasably clamped therein when the clip leg 14 is released and spring biased by its resiliency toward its coacting leg 12.

It will thus be readily apparent that the holder 7 provides a number of spring clips or clamps for holding a plurality, preferably four, different articles used in connection with applying make-up so that each of said articles is readily convenient for use and so that the clip can be removed from a pocketbook or handbag with each of the articles supported thereby and thus made conveniently available eliminating the need for searching through a handbag to find the individual articles as is now commonly required. It will also be noted that each of the articles held by the resilient holder cooperates in maintaining the resilient gripping engagement of the holder with at least one of the other objects thus providing a unique construction wherein the articles engaged assist in the normal functioning of the holder 7.

Whereas the holder 7 has been illustrated and described in its presently preferred form of Figures 1 to 4 and wherein the parts 9 to 22 inclusive are formed from a single strip of resilient material, such as spring steel, it is also contemplated that the parts may be formed of other materials and that the mirror engaging clip 8 may be formed of sections as illustrated, for example, in Figure 5 wherein the legs 11a and 10a are connected at their upper ends by intermediate portions formed of sections 33 and 34 which constitute inturned extensions of the upper ends of the legs 11a and 10a, respectively, and which are provided with aligned barrel portions 35 and 36, respectively through which extends a pivot pin 37 having headed ends. The legs 10a and 11a are thus swingably supported for movement toward and away from one another by this mounting of the barrel portions on the pin 37 and a spring 38 is wound about the intermediate portion of the pin 37 between adjacent barrel portions 35 and 36 and has outwardly extending terminals engaging the outer sides of the portions 33 and 34 for urging the legs 10a and 11a toward one another. Figure 6 illustrates another modification similar to Figure 5 except that the legs 10b and 11b at their upper ends terminate in inwardly extending arms 39 and 40, respectively and the arms 40 are spaced a greater distance apart than the arms 39 and the free ends of the arms 40 straddle the free ends of the arms 39. A pin 41 extends through and is journaled in the free ends of each of the arms 39 and 40 for pivotally mounting the legs 10b and 11b and said pivot pin 41 has a coiled spring 42 wound thereon the ends of which bear on the upper ends

of the legs 10b and 11b for yieldably biasing said legs toward one another.

Various other modifications and changes are contemplated and may obviously be resorted to, without departing from the spirit or scope of the invention as hereinafter defined by the appended claims.

I claim as my invention:

1. A holder of the character described comprising a spring clip having legs spring biased toward one another and adapted to detachably clamp a first article therebetween, one leg of said spring clip having an outwardly turned back extension at its free end normally disposed against the outer side and said leg, said turned back extension terminating in an outwardly turned back portion having an outturned terminal portion extending laterally away from said leg extension and forming a resilient clamping jaw, an adjustable clamping jaw having hook portions slidably engaging said leg extension and slidably movable toward and away from the resilient clamping jaw for releasably engaging a second article to be supported between said clamping jaws, said hook portions fulcruming on said leg extension when the resilient clamping jaw is in yieldable engagement with the second article supported between said jaws to cause said hook portions to frictionally engage the leg extension to retain the slideable clamping jaw in an article gripping position, said leg having an intermediate part of reduced width providing recesses along each side edge thereof in which portions of the hooks of the adjustable clamping jaw slidably fit for limiting sliding movement of said hooks and sliding movement of the adjustable clamping jaw toward and away from said resilient clamping jaw.

2. A holder of the character described comprising a first spring clip having a first leg, a second leg, and an intermediate portion extending between and connecting corresponding ends of said legs, said legs being spring biased toward one another and being adapted to detachably clamp a first article therebetween, said first leg having an outwardly turned back extension at its opposite free end extending to beyond said intermediate portion of the first clip, said second leg

having an outwardly turned back extension at its opposite free end normally disposed against the outer side thereof and extending to beyond said intermediate portion, said last mentioned turned back extension terminating in an outwardly turned back portion, the portion of said first leg and second leg extensions disposed beyond said intermediate portion being bowed toward one another and combining with said intermediate portion to provide a second article engaging clip adapted to yieldably clamp a second article releasably therein, said outwardly turned back portion of the second leg extension having an outturned terminal portion extending laterally away from the second leg extension and forming a resilient clamping jaw, an adjustable clamping jaw having hook portions slidably engaging the second leg extension and slidably movable toward and away from the resilient clamping jaw for releasably engaging a third article to be supported between said clamping jaws, said hook portions fulcruming on the second leg extension when the resilient clamping jaw is in yieldable engagement with an article supported between said jaws to cause said hook portions to frictionally engage the second leg extension to retain the slideable clamping jaw in an article gripping position, said second leg having an intermediate part of reduced width providing recesses along each side edge thereof in which portions of the hooks of the adjustable clamping jaw slidably fit for limiting the sliding movement of said hooks and the sliding movement of the adjustable clamping jaw toward and away from said resilient clamping jaw.
